US0D1057991S

(12) **United States Design Patent** (10) **Patent No.:** **US D1,057,991 S**
(45) **Date of Patent:** **** Jan. 14, 2025**

(54) **FLUID ANALYSIS APPARATUS**

(71) Applicant: **Procomcure Biotech GmbH**, Thalgau (AT)

(72) Inventor: **Kamil Önder**, Eugendorf (AT)

(73) Assignee: **Procomcure Biotech GmbH**, Thalgau (AT)

(**) Term: **15 Years**

(21) Appl. No.: **29/843,065**

(22) Filed: **Jun. 17, 2022**

(51) LOC (15) Cl. **24-02**
(52) U.S. Cl.

USPC **D24/216**

CLAIM

The ornamental design for a fluid analysis apparatus as shown and described.

DESCRIPTION

FIG. 1 is a top plan view of a fluid analysis apparatus in a first condition of use;

FIG. 2 is a top plan view of a fluid analysis apparatus in a second condition of use;

FIG. 3 is a top plan view of a fluid analysis apparatus in a third condition of use;

FIG. 4 is a top plan view of a fluid analysis apparatus;

FIG. 5 is a right side perspective view of a fluid analysis apparatus;

FIG. 6 is a left side perspective view of a fluid analysis apparatus, shown in an open configuration for clarity of disclosure; and,

FIG. 7 is a front view thereof, shown in an open configuration for clarity of disclosure.

In the drawings, the equal-length broken lines depict portions of the fluid analysis apparatus and form no part of the claimed design.

1 Claim, 7 Drawing Sheets
